UNITED STATES PATENT OFFICE.

FRANKLIN W. MANN AND CLARENCE H. FARRINGTON, OF MILFORD, MASSACHUSETTS; SAID FARRINGTON ASSIGNOR TO SAID MANN.

MACHINE FOR GRINDING BONE.

SPECIFICATION forming part of Letters Patent No. 409,480, dated August 20, 1889.

Application filed February 8, 1889. Serial No. 299,152. (No model.)

To all whom it may concern:

Be it known that we, FRANKLIN W. MANN and CLARENCE H. FARRINGTON, both of Milford, county of Worcester, State of Massachusetts, have invented an Improvement in Machines for Grinding Bone, of which the following description, in connection with the accompanying drawings, is a specification, like letters on the drawings representing like parts.

In the manufacture of bone-meal for poultry it has heretofore been customary to crush or grind the dried bone; but such meal is not as nutritious as when made from fresh bone having thereon the scrap-meat and within the marrow.

This invention has for its object to improve the construction of grinding or cutting machines, as will be hereinafter described, whereby fresh bone having the meat thereon and the marrow within it may be ground or cut.

Figure 1 shows in vertical section a machine for grinding bone embodying this invention, the operating-handle being broken off; Fig. 2, a plan view of the machine shown in Fig. 1, the cross-bar employed for moving the platen or follower being removed; Fig. 3, an underside view of the rotatable knife carrying bottom plate; and Fig. 4 a perspective view of one of the knives.

The cylinder a is provided at its lower end at each side with lugs a' , by which it is secured to the side frames a^2 by suitable bolts a^3 . The cylinder a is provided with a diametrically-arranged partition-wall a^4 , extended from the top nearly to the bottom, and leaving sufficient space under it for the passage of the knives in their rotation. Said cylinder is also provided at the center with a vertical standard or support a^5 , formed integral with said division-wall.

A bottom plate b is loosely mounted on a support or rod b' , arranged vertically within the support a^5 , and held rigidly by the set-screw b^2 , a nut or flange b^3 being turned on or formed integral with the bar a' to assist in holding the said bottom plate in position. The bottom plate b is made larger in diameter than the cylinder a , and is provided outside

the said cylinder with teeth to form a beveled gear b^4 .

A shaft c , having its bearings in a block c' , secured to one of the side frames a^2 by the aforesaid bolts a^3 , has fixed to it a beveled gear c^2 , which engages and drives the beveled gear b^4 , said shaft c being rotated by a hand-wheel c^3 , also fixed to it.

The bottom plate b is provided with a series of holes extending through it and arranged adjacent to lugs d , formed integral with said plate, the said holes being large enough to receive the cutting-edges of the knives d' , and also to afford a passage for the exit of the material after it is ground or cut.

The knives which I preferably employ consist of a flat bar grooved longitudinally, as at 2, and having a slot 3 and beveled at one end, as best shown in Fig. 4, to form, in co-operation with the grooves 2, a series of sharp teeth.

The knives d' are secured to the lugs d by set-screws d^2 , passing through the slots 3, and set-screws d^3 pass through the lower projecting ends of said lugs and bear against the rear ends of the knives d' , said set-screws d^2 holding the knives rigidly, but affording proper adjustment. The knives d' , secured adjustably to the lugs, as described, are inclined with relation to the bottom plate b , as shown in Fig. 3, so that the cutting-edges only project slightly above the upper surface of said plate.

A platen or follower e , of suitable size to enter and move freely within the cylinder a , is secured to a yoke or frame e' , the said platen or follower being slotted to receive the division-wall a^4 . The yoke is arranged to slide freely on the rod b' , normally resting by gravity upon the bottom plate b , or upon any material contained in the cylinder, and a cross-bar or handle f is turned upon the screw-threaded end f' of said rod b' to force the yoke and follower down.

In operation the material is placed in the cylinder a directly upon the bottom plate, and the handle-bar f turned to force the platen down firmly upon the material. The bottom plate is then revolved by the hand-wheel, and the knives act to cut the material. We preferably arrange the knives at different distances

from the center or axis of rotation of the bottom plate, as shown in Fig. 3.

By providing grooved knives, as shown, they may be ground by the user upon a flat-surfaced stone without destroying or decreasing the size of the teeth.

We claim—

1. In a machine for grinding or cutting bone, the cylinder *a*, rotatable bottom plate 10 and knives carried by it, and means, substantially as described, for rotating said bottom plate, combined with the platen or follower *e*, yoke *e'*, and cross-bar or handle *f*, and the fixed support or rod *b'*, having the screw-threaded end *f'*, whereby the platen may be moved vertically, substantially as described.

2. In a machine for grinding or cutting bone, the fixed cylinder *a*, having the fixed division-wall extended from the top to near 20 the bottom of said cylinder, combined with the rotatable bottom plate and knives carried by it, and means, substantially as described, for rotating the bottom plate, the split platen or follower, slotted to receive the division-wall, and means, substantially as described, 25 for moving it independently of the bottom plate, substantially as described.

3. In a machine for grinding or cutting bone, the fixed cylinder *a* and partition-wall

a', combined with the rotatable bottom plate, 30 knives carried by it and inclined with relation thereto, and means, substantially as described, to rotate said plate, the split platen or follower, its yoke, and the cross-bar *f* and fixed support *b'*, having the screw-threaded 35 end *f'*, as and for the purposes set forth.

4. In a machine for grinding or cutting bone, the fixed cylinder *a* and division-wall *a'*, combined with the rotatable bottom plate *b*, having a series of holes therein at different 40 distances from its center, lugs *d* adjacent to said holes, adjustable slotted knives carried by said lugs, inclined with relation to the bottom plate, set-screws *d²* *d³* to adjust said knives, and means, substantially as described, 45 for rotating said plate, and the slotted platen or follower, its yoke and cross-bar, and the fixed support *b'*, having the screw-threaded end *f'*, substantially as described.

In testimony whereof we have signed our 50 names to this specification in the presence of two subscribing witnesses.

FRANKLIN W. MANN.

CLARENCE H. FARRINGTON.
